UNITED STATES PATENT OFFICE.

CHARLES H. NUMAN, OF NEW YORK, N. Y.

DESIGN FOR AN INKSTAND.

No. 39,825.

Specification for Design.

Patented Feb. 16, 1909.

Application filed December 7, 1908. Serial No. 466,429. Term of patent 7 years.

To all whom it may concern:

Be it known that I, CHARLES H. NUMAN, a citizen of the United States, residing at New York city, in the county and State of New York, have invented a new, original, and ornamental Design for an Inkstand, of which the following is a specification, reference being had to the accompanying drawings, forming a part thereof, and in which—

Figure 1 is a top view; Fig. 2 a side view, and Fig. 3 a front view of an inkstand embodying my design.

The leading features of my design pertain to the ornamental form and configuration of the inkstand as a whole.

I claim:

The ornamental design for an inkstand, as shown.

CHARLES H. NUMAN.
